ATTACHMENT FOR CONDUCTORS

Arthur O. Austin, near Barberton, Ohio, assignor,
by mesne assignments, to The Ohio Brass Com-
pany, Mansfield, Ohio, a corporation of New
Jersey

Application July 27, 1933, Serial No. 682,448

6 Claims. (Cl. 173—251)

This invention relates to attachments for conductor clamps, and has for one of its objects the provision of a convenient device for securing protector rods or other similar devices to a conductor at the point where it leaves the clamp.

A further object of the invention is to provide means for securing a protective device to conductor supports on transmission lines already installed.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is an elevation of a dead end clamp having a conductor supported thereby and equipped with one embodiment of the present invention.

Fig. 2 is a fragmentary, vertical, sectional view of the attachment shown in Fig. 1.

Figs. 3, 4 and 5 are sections on lines 3—3, 4—4 and 5—5 respectively of Fig. 2.

Electrical conductors, and especially conductors of large size, are subject to vibration, which has a tendency in time to crystallize the conductor at its point of support and cause breakage of the strands. Various devices have been designed to minimize or prevent this effect by damping out the vibrations and by distributing the bending of the conductor at its support over an extended portion of the conductor. One form of device for this purpose is shown in Patent #1,873,798, granted

August 23, 1932 to Theodore Varney. The device described in that patent comprises a plurality of tapered bars or rods disposed about the conductor at its point of support and extending along the conductor at either side of the support. The arrangement requires special clamping means for securing the reinforcing rods to the conductor and for attaching the bundle of rods with the enclosed conductor to the conductor support. The arrangement makes it difficult or impossible to apply the device to conductors already installed. The present invention provides means by which a reinforcement similar to that of the Varney patent may be applied to a conductor without the provision of special clamps or conductor supports, and by which the reinforcing rods may be readily applied to conductors already installed.

In the embodiment of the invention shown in the drawing, the numeral 10 designates a conductor clamp which may be similar to that shown in my prior Patent #1,002,113. While I have

shown the attachment applied to a dead end clamp, it is to be understood that it may be applied also in a like manner to suspension clamps distributed along the conductor. The invention comprises an extension member 11 having one end 12 shaped to fit over the end of the clamp 10 and provided with a projecting portion 13 having a seat for receiving the reinforcing rods 14 disposed about the conductor 15. The portion 12 is provided with laterally extending bosses 16 for receiving the ends of a U-bolt 17, which engages the upper portion of the clamp 10 and thus secures the attachment 11 firmly in position on the end of the clamp 10. The end 12 of the clamp 11 is provided with projecting ridges 18 and 19 which provide grooves on the inner side of the attachment wall for receiving ribs 20 and 21 respectively on the clamp 10. It will be seen that this arrangement firmly secures the attachment 11 to the end of the clamp 10 so that it is rigidly held in position on the clamp and forms, in effect, an extension on the end of the clamp. The projecting portion 13 is provided with a seat of proper size and contour to support the reinforcing rods 15 on the conductor 10 and permit the conductor to continue from the end of the clamp 10 without deflection. The keeper 22 engages the upper rods 14 and is provided with ears 23 which extend into pockets 24 in the side walls of the extension 13 so as to provide overlapping portions with the side walls to hold the rods 14 in position upon the cable 15 and to clamp the rods firmly in the support 13 and tightly about the conductor 15. The keeper 22 is held in place by U-bolts 25 having nuts 26 for clamping the U-bolts in place.

It will be understood that various modifications will readily suggest themselves to those skilled in the art without departure from the spirit and scope of the invention, as defined in the appended claims.

I claim:

1. The combination with a conductor and a support therefor, of an attachment rigidly and removably secured to said support and having a portion extending beyond said support along said conductor, and flexible reinforcing rods carried by said extending portion and engaging said conductor beyond said extending portion for minimizing the effects of vibration of said conductor.

2. The combination with a conductor and a support therefor having a seat portion for receiving said conductor, of an attachment for said support having a seat portion, one end of which is rigidly clamped to said support in overlapping

- relation to the seat portion of said support and the other end of which extends beyond said support along said conductor, and reinforcing means for the conductor disposed in the extending end 5 of said seat portion of said attachment and terminating along said conductor at a point spaced from said attachment, said conductor extending beyond said point.
3. The combination with a conductor and a support therefor provided with a seat for said conductor, of reinforcing means for said conductor abutting the end of said support and extending along said conductor from said end, and an attachment for securing said reinforcing means to said conductor and to said support, said attachment being disposed in overlapping relation with said support and with said reinforcing means, and clamped to said support and to said reinforcing means.
4. The combination with a conductor and a support therefor having a seat for said conductor, of reinforcing means for said conductor comprising rods having the ends thereof disposed in abutting relation to the end of said support, and 25 an attachment for securing said rods to said conductor and to said support, said attachment having one end thereof shaped to conform to the outer surface of said support and having an extension overlapping the ends of said reinforcing rods, and means for clamping said attachment to 30

said support and to said reinforcing rods in overlapping relation to the adjacent ends of said support and reinforcing rods.

5. The combination with a conductor and a support therefor having a seat for said conductor, 5 said support having external projections adjacent the end thereof, of an attachment having a recess therein shaped to conform to the outer surface of said support and having depressions for receiving the projections on said support, and means for clamping said attachment to said support, said attachment having a portion thereof extending beyond the end of said support and provided with a seat for receiving reinforcing means disposed about the conductor.

6. The combination with a conductor and a support therefor having a seat for said conductor, of reinforcing rods disposed about said conductor and having the ends thereof disposed in abutting relation to the end of said support, and an attachment for securing said ends to said conductor and to said support, said attachment comprising a trough shaped member forming a seat having one end thereof shaped to conform to the outer surface of the end of said support, and 20 having the other end thereof shaped to engage 25 said rods, and clamping means for securing said attachment to said support and for securing said rods in said seat.

ARTHUR O. AUSTIN. 30
